UNITED STATES PATENT OFFICE.

EDWARD TIMBS, OF TORRANCE, CALIFORNIA.

COMBINATION ROTARY AND CABLE TOOL DRILLING RIG.

Application filed October 28, 1920. Serial No. 420,232.

To all whom it may concern:

Be it known that I, EDWARD TIMBS, citizen of the United States, residing at Torrance, in the county of Los Angeles and State of California, have invented certain new and useful Improvements in Combination Rotary and Cable Tool Drilling Rigs, of which the following is a specification.

The objects of my invention are, first;

- 10 to construct a combination drilling rig that is adapted to decrease the ground area necessary to operate the same, and that will require only one side of the derrick, to eliminate the use of bull ropes or chains over the derrick floor, to increase the clear space thereon, and to adapt the housing in of all chains and belts, second;—to use an improved type and arrangement of power transmission, with a swiveled walking beam
- 20 that is adapted to facilitate the operation of a cable tool rig without the disconnection of the parts thereof, third;—to use an interchangeable rig of the said class that may be driven by a single power unit of any
- 25 description for drilling oil, gas, or water wells, fourth;—to use a power transmission means that is adapted to reduce the size of all sprockets to less than fifty teeth, and to eliminate the use of wood in the construction of the same, to increase the strength and prevent deterioration.

Further objects are to drive the rotary machine, which is used for hydraulic drilling, by a shaft the same as the present shaft drive attachment except that the power is applied directly at the end of the rotary driving shaft, and is mechanically controlled so that the rotary machine may be stopped independently of the engine, or motor.

- 40 The present type drum for the draw works is keyed to its shaft, and it is found that the three bearings used are difficult to keep in alignment, and if kept rigidly adjusted will create undue friction on the shaft necessitating the use of extra heavy snatch blocks to bring the hook and elevators down at a predetermined speed, therefore I run my drum loose on its shaft, on only two bearings, and thus the heavy snatch blocks now in common
- 45 use will not be necessary.

My calf wheel, or draw works, is con-

trolled similarly to the present draw works, with clutches of the bevel jaw type arranged so that the high speed can take the load from the low speed by automatically throwing out the low speed clutch, or vice versa. My draw works, which I also use as a calf wheel is located in the present calf wheel position to dispense with the present type of draw works now in common use on the "S" side of the derrick; and I place my bull wheel beside the calf wheel which is driven thru the calf wheel shaft to replace the present dangerous rope driven bull wheel on the "E" side of the derrick, thus eliminating the obstruction on the derrick floor and sides, and to convenience the handling of drilling materials.

My sand reel is driven by a friction clutch, and is controlled by a band brake to overcome the excessive wear of the rope lagged band wheel used in the present sand reel drive. My band brake being lined with nonburning material is more efficient than the present sand reel back-brake which is of wood and has only a small portion of braking surface, thus causing a tendency to burn.

By eliminating the present wooden band wheel, and the overhanging sprocket and clutch on the walking beam crank shaft, I can use my balanced crank shaft with the bearings on close centers to obtain a more rigid drive, and I in turn locate my sand reel so that its shaft is used as a counter shaft for obtaining the required speed reduction, to operate the said walking beam.

I eliminate the use of more than one power unit by driving the hoisting drums by sprockets and a chain direct from the engine shaft to a line shaft, and from this line shaft by sprockets and a chain for a high speed, and another pair of sprockets and a chain for a low speed. I apply these drives by clutches on the line shaft, and when disengaged I can operate the cat heads in the usual manner. My drums are so arranged that they can run freely on their shafts when lowering drill pipe, casing, or tools, and so that they in turn revolve with the shaft when pulling a load.

I use a crown block, not shown, on the top portion of the derrick 85, consisting of

a crown sheave, a sand line sheave and any predetermined number of casing line sheaves. The line from the bull wheel 8 passes over the said crown sheave, and is connected to a string of cable tools in drilling position, not shown. I use the slow speed and heavy duty line from the calf wheel 7 for raising and lowering casing, by passing the same over the casing line sheaves, thence to the snatch block, not shown, which in turn holds the hook and elevators, not shown. The snatch block sheaves and crown block sheaves are adapted to give a predetermined load reduction on the calf wheel 7. The said calf wheel 7 in connection with a high speed drive becomes a draw works, for a hydraulic-rotary drilling machine, to raise and lower drill pipe, and is adapted to use the same crown block connection therewith. A sand line, not shown, is run from the sand reel 42, over the said sand line sheave, and connects directly to a bailer or sand pump, not shown.

With the foregoing objects in view, the invention resides in the combination of details and construction hereinafter described and claimed.

I attain these objects by the mechanism illustrated in the accompanying drawings, in which:

Figure 1 represents a plan view of my rig, with a portion of the derrick omitted.

Figure 2 represents a side elevation of my rig, with a portion of the derrick omitted.

Figure 3 represents a section on line 3—3 of Figure 1.

Figure 4 represents a side elevation of my swivel type walking beam, assembled.

Figure 5 represents a plan view of Figure 4, showing the position of the walking beam when clearing the well.

Figure 6 represents a front view of Figure 4, showing the position of the walking beam when clearing the well.

Figure 7 represents a side elevation of the swivel for my walking beam.

Figure 8 represents a section on line 4—4 of Figure 7.

Figure 9 represents a plan view of Figure 7, with the saddle removed.

Figure 10 represents a plan view of my rig, showing a modified form of power installation when using an electric motor.

Referring to the drawings in which like characters of reference designate similar parts, 1 represents the engine with the pulley 39 secured to the crank shaft thereof on the outboard side, a flywheel 38 is in turn secured to the inboard side thereof, the said engine 1 is adapted to connect to the shaft 26 of the bevel drive 47, the bevel gear 48 is operatively mounted on the shaft 26 and is adapted to mesh with the bevel pinion 49, the clutch 50 is mounted on the shaft 26

and is adapted to drive the bevel gear 48, the bevel drive 47 is adapted to connect to the rotary 6 by the sleeve 56. The sprocket 10 is secured to the shaft 26, and the sprocket 13 is in turn mounted on the shaft 29, the chain 22 operatively meshes between the said sprockets 10 and 13, the said shaft 29 is adapted to be operatively mounted on posts 60, the cat heads 58 and 59 are secured to the outboard ends of the shaft 29, the clutches 51 and 52 are mounted on the shaft 29 and are adapted to drive the sprockets 14 and 18 respectively. The shafts 30 and 31 are mounted on the said posts 60 parallel with the shaft 29, and are secured together by the coupling 37, the sprockets 15 and 19 are secured to the shaft 31, the clutches 53 and 54 are mounted on the shafts 30 and 31 respectively, and are adapted to drive the bull wheel 8 and the calf wheel or draw works drum 7 respectively, the said bull wheel 8 is operatively mounted on the shaft 30, and the said calf wheel 7 is operatively mounted on the shaft 31, the chain 20 meshes operatively between the sprockets 14 and 15, and the chain 21 in turn meshes operatively between the sprockets 18 and 19.

The shafts 34 and 27 are adapted to be operatively mounted on the posts 61, and are secured together by the coupling 36, the pulley 40 is secured on the shaft 34, and is connected to the pulley 39 of the said engine 1 by the belt 25, the clutch 55 is mounted on the shaft 27 and is adapted to drive the clutch-sprocket 11, the sand reel 42 is operatively mounted on the said shaft 27, the clutch 89 is also mounted on the shaft 27 and is adapted to drive the sand reel 42, the brake 43 is in turn mounted on the sand reel 42. The shaft 28 is adapted to be operatively mounted on the jack posts 62, the sprocket 12 and the counterweight 41 are securely mounted thereon, the chain 23 is adapted to operatively mesh between the sprockets 11 and 12, the crank 64 is in turn secured to the outboard portion of the shaft 28.

The samson post 63 is mounted on the main sill 87, and is adapted to accommodate the cap 65, the bearing 66 is mounted on the cap 65 by the pin 72, with the rollers 68 therebetween, the trunnion 67 is operatively mounted on the bearings 66 and is integral with the saddle 71, the walking beam 57 is in turn secured on the saddle 71, the bearings 75 are integral with the cap 65 and the said bearings 75 are in turn adapted to receive the worm 73 therebetween, the shaft 76 is operatively positioned in the bearings 75 and is secured to the worm 73, the worm gear 74 is integral with the bearing 66, and is adapted to mesh with the worm 73, and the sheave 69 is securely mounted on the shaft 76 and is adapted to 130

accommodate the chain 70. The walking beam 57 is adapted to operatively hold the stirrup 80, the knuckle joint 78 is in turn operatively secured to the stirrup 80 and the pitman 77, the pitman 77 is secured to the knuckle joint 79, and the said knuckle joint 79 is operatively fulcrumed on the crank pin 81. The T iron 82 is adapted to bear on the walking beam 57 and is integral with the temper screw, not shown.

The motor 83 shows a modified form of power transmission connected to the shaft 32 by the coupling 35, the shaft 32 is operatively positioned in one end of the plate 84, and the shaft 26 is in turn operatively positioned in the opposite end of the said plate 84, the sprocket 17 is securely mounted on the shaft 32, and the sprocket 16 is securely mounted on the shaft 26, the chain 24 is adapted to be operatively positioned between the said sprocket 17 and 16, the pulley 39 and the sprocket 10 are thence adapted to form a unit with the transmission as hereinbefore described.

A modified form of power transmission may be applied by omitting the bevel gear 48, the bevel pinion 49, the sleeve 56, and the rotary machine 6, for cable tool drilling, by transmitting the power from the engine 1 to the shaft 29, thru the shaft 26, the closed clutch 50, the sprocket 10, the chain 22, and the sprocket 13 respectively.

With the operation of my combination rig, when using the same for rotary drilling, the engine 1 is adapted to drive the shaft 26, the clutch 50 is in turn adapted to control the operation of the rotary machine 6 thru the bevel gear 48, and the bevel pinion 49 of the bevel drive 47, the sprocket 10 is adapted to drive the sprocket 13 thru the chain 22 direct from the engine, the clutch 52 with the coupling 37 disengaged is adapted to control the slow speed operation of the draw works, (which comprises the shaft 31 with all the mechanism thereon) thru the sprocket 18, the chain 21, and the sprocket 19 respectively, and the clutch 51 is in turn adapted to control the operation of the said draw works when a high speed is desired by transmitting the power thru the sprocket 14, the chain 20, and the sprocket 15 respectively. I can also use my combination rig for cable tool drilling, with the operation of my calf wheel 7, and bull wheel 8, by engaging the clutch 50 (with the bevel gear 48, the bevel pinion 49 and the rotary machine 6 removed) to drive the shaft 29, thru the sprocket 10, the chain 22, and the sprocket 13 respectively, the power is thence transmitted to the said calf wheel 7 (or draw works), in like manner as when used for rotary drilling.

With the coupling 37 and clutch 53 engaged, and the clutch 54 disengaged, the bull wheel 8 and calf wheel 7 may be driven

at a high speed in like manner as the draw works, by opening the clutch 52 and transmitting the power thru the closed clutch 51, the sprocket 14, the chain 20, the sprocket 15, and the shaft 31 respectively, and thence thru the said coupling 37 and shaft 30, to the bull wheel 8. The bull wheel 8 and calf wheel 7, may also be driven at a slow speed by disengaging the said clutch 51, and transmitting the power thru the closed clutch 52, and thence thru the sprocket 18, the chain 21, the sprocket 19, the shaft 31, and the closed clutch 54 respectively, to the said coupling 37.

The brakes 45 and 46 are adapted to control the reeling out of the calf wheel 7, which may also be used as a draw works, and the brake 44 is in turn adapted to control the reeling out of the bull wheel 8, which is integral with the said cable tool rig.

The cat heads 58 and 59 are driven by the shaft 29 independently of the draw works, thru the shaft 29.

The belt 25 is adapted to transmit power thru the pulley 39 from the said engine 1, to the pulley 40, the shaft 34, the coupling 36, and the shaft 27 respectively, the clutch 89 is in turn adapted to drive the sand reel 42, the brake 43 is adapted to control the load on the said sand reel 42, the clutch 55 is in turn adapted to control the operation of the clutch sprocket 11, the shaft 28 is driven by the said clutch sprocket 11, thru the chain 23, and the sprocket 12 respectively. The walking beam 57 is driven by the crank 64, thru the crank pin 81, the knuckle joint 79, the pitman 77, the knuckle joint 78, and the stirrup 80 respectively. The counter weight 41 is adapted to balance the rotary action of the said crank 64.

The walking beam 57 is adapted to carry the T iron 82 clear of the well 86, by a swivelling motion of the said walking beam on the rollers 68, and is operated by a sheave wheel 69 and a chain 70, thru the shaft 76, the worm 73, and the worm gear 74 respectively. The walking beam 57 is reciprocated over the said well 86 in the usual manner on the trunnion 67.

A modified form of power installation is disclosed in a motor 83, where an added speed reduction is used to reduce the high speed of the said motor 83 in proportion to the chosen speed of the said shaft 26, the power is thence transmitted thru the coupling 35, the shaft 32, the sprocket 17, the chain 24, and the sprocket 16 respectively, and is thence transmitted to the said shaft 26.

Having thus described my invention, I claim:

1. In a cable tool drilling rig of the class described, in combination with a single power means, adapted to drive a calf wheel, a bull wheel, and a sand reel, a swiveled

walking beam and a knuckle jointed pitman, adapted to operate the said walking beam by the power means, and to swing with the said walking beam when clearing the well, as set forth.

2. In a cable tool drilling rig of the class described, a multiple speed power transmission means, adapted to drive or release

a bull wheel, a sand reel, or a swiveled walking beam; a knuckle jointed pitman, adapted to operate the walking beam by the said power means, or to swing with the said walking beam clear of the well, as set forth.

In testimony whereof I affix my signature

EDWARD TIMBS.
